ACCESSORIES HOLDER FOR A SHOWER

Dwight N. Woooters, Wooster, Ohio, assignor to Rubbermaid Incorporated, Wooster, Ohio

Filed June 14, 1972, Ser. N. 262,546

Term of patent 14 years

Int. Cl. D6—04

U.S. Cl. D6—91

FIG. 1

FIG. 2

FIG. 4

FIG. 3

FIG. 5

FIG. 6

FIG. 1 is a front elevational view of an accessories holder for a shower embodying my new design.

FIG. 2 is a side elevational view thereof.

FIG. 3 is a vertical sectional view on line 3—3 of FIG. 1.

FIG. 4 is a top plan view thereof.

FIG. 5 is a cross-sectional view on line 5—5 of FIG. 1.

FIG. 6 is a cross-sectional view on line 6—6 of FIG. 1.

I claim:

The ornamental design for an accessories holder for a shower, as shown.
